UNITED STATES PATENT OFFICE

IRA C. COLLIER AND ELSA H. COLLIER, OF CORONADO, CALIFORNIA

DETACHABLE SHOE HEEL

Application filed December 31, 1928. Serial No. 329,577.

Our invention relates to detachable shoe heels and the objects of our invention are: first, to provide a readily detachable heel; second, to provide means for securely removably attaching a heel to a shoe; third, to provide interlocking means on shoe and detachable heels for permitting the quick replacement of the heel by the wearer of the shoe; fourth, to provide a combination of shoe and a plurality of varied colored heels any one of which may be quickly and easily secured to the shoe to match the costume of the wearer of the shoe; fifth, to provide a heel which is secured to the shoe by simple means forming a rigid and permanent part of the heel and of the shoe; sixth, to provide readily removable locking means for preventing accidental displacement of the heel when in position; seventh, to provide means for this purpose which are normally concealed from view; eighth, to provide means for removably securing the heel which firmly clamps the heel in position and which will not readily loosen or break away; and, ninth, to provide a heel attaching device which is economical of manufacture, simple of application, durable, and which will not readily deteriorate or get out of order.

With these and other objects in view as will appear hereinafter, our invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a view partly in section of the heel and the rear lower foot portion of the shoe clamped and locked together; Fig. 2 is an elevational view of the detached heel looking from the front end thereof; Fig. 3 is a plan view of the detached heel seen from above, and Fig. 4 is a plan view of the rear lower end of the shoe with the heel removed.

Similar characters of reference refer to similar parts and portions throughout the several views of the drawings.

The keeper plate 1, catch members 2, lock

screw 3, sleeve 4 and lock nut 5, form the principal parts and portions of our invention.

The keeper plate 1 is made preferably of relatively thin, resilient sheet metal, such as tinned sheet iron, of substantially rectangular shape, and of a width and length somewhat smaller than the upper end of the heel, as clearly indicated in Fig. 3 of the drawings. The one end of the plate is preferably rounded off corresponding to the curvature of the back portion of the heel and is provided with a plurality of keyhole-shaped slots 1^a. In the preferred form, three of these slots are provided, one being positioned at the curved end of the plate in the median line thereof, while the other two occupy the corners at the opposite end of the plate. The slots 1^a have a narrow, elongated portion and an enlarged rounded portion at their one end and are so arranged in the plate that the elongated portion points towards the curved or rear end of the plate. The plate 7 is secured by means of the cobbler's nails 1^b to the upper end of the heel which is provided with cavities 7^a providing a clearance underneath the slotted portion of the plate. The catch members 2 which are secured to the rear lower foot portion of the shoe 6, comprise a substantially cylindrical rivet portion 2^a, intermediate shoulder portions 2^b, an enlarged, cylindrical portion 2^c, and a cone-shaped head portion 2^d. The latter is beveled outwardly and forms shoulders for engaging the margins of the elongated slots 1^a. The diameter of the head 2^d is such that it passes freely through the enlarged, circular portion of the slots 1^a, while the cylindrical portions 2^c of the catch 2 is adapted to slide in the elongated portion of the slots 1^a.

The catch members 2 are spaced in the same manner as the slots 1^a of the keeper plate and are so located on the shoe 6 that when the catch members occupy the narrow end of the slots 1^a the heel occupies the correct position on the shoe 6, as shown in Fig. 1. The projecting portion of the catch member heads 2^d extend within the cavities 7^a in the heel.

The front, upper portion of the detachable

heel is provided with a forwardly extending lip portion 7^b. Near the front margin of the lip portion 7^b we provide an aperture through which a sleeve 5 is placed. The sleeve 5 is held in position by flanging over the end margins thereof. A corresponding sleeve or lock nut 4 is secured to the shoe 6 in like manner. The sleeve 4 is provided with internal threads 4^a for receiving the threaded portion of a lock screw 3 which extends through the sleeve 5 in the lip 7^b of the heel. The lock screw 3 is provided with detents 3^b intermediate its end and a head portion 3^a at its outer end, thereby limiting longitudinal displacement of the screw within the sleeve 5. The detents 3^b which may be formed by pinching out a small portion of the metal forming the screw, do not in any way hinder the rotation of the screw with in the sleeve 5. At the outer end of the screw 3 a grip portion 3^c is provided enabling the screw to be conveniently turned by hand.

In order to prevent the inner end of the lock screw 3 from being in the way when the heel is being slid into position on the shoe, the sleeve 5 is provided with pockets 5^a extending a portion of its length and adapted to receive the detents 3^b and to permit the screw 3 to occupy the position indicated in dotted lines in Fig. 1. It is obvious that instead of the pockets 5^a, the upper portion of the sleeve 5 could be increased in diameter sufficiently to clear the detents 3^b.

In attaching a heel to a shoe, the heads 2^a of the catch members are registered with the enlarged ends of the slots 1^a in the keeper plate 1. In this position the rear end of the heel will occupy the position indicated in dotted lines in Fig. 1. The heel is then pushed forwardly along the shoe 6 until the portion 2^c of the catch occupies the rear or narrow end of the slots 1^a. At this point the screw 3 will register with the lock nut 4 and may then be advanced into engagement with the threads thereof and screwed home. This will then prevent any possibility of the heel being forced out of engagement with the keeper plate and as it is possible to adequately secure the keeper plate by means of the nails 1^b to the heel and the method of securing the catch members 2 by riveting over their inner ends 2^b against the inner side of the shoe, a rigid attachment of the heel to the shoe is obtained. At the same time the heel may be very quickly removed and replaced by another, either for the purpose of replacing a worn heel or for altering the color scheme, such as would be the case if it were desired to match the color of the heel of a shoe with other apparel of the costume worn. Instead of a number of shoes of different color it is possible to have a single shoe of a neutral color and a number of heels of various colors. As the heels wear out very much more quickly than the rest of the shoe, the wearer is able to replace a worn

heel by a new heel and have the former repaired without being in the least inconvenienced.

While the illustrations show our device used in connection with a lady's shoe having French heels, it is obvious that it is equally applicable to any other type of shoe and while we have shown and described a particular construction, combination and arrangement of parts and portions, we do not wish to be limited to this particular construction, combination and arrangement but desire to include in the scope of our invention the construction, combination and arrangement substantially as set forth in the appended claims.

Having thus described our invention, what we claim as new and desire to secure by Letters Patent is:

1. The combination with the foot portion of a shoe, of a detachable heel, a keeper plate secured to the upper end of said heel, co-operating catch members secured to said shoe adapted to engage said keeper plate and clamp said heel in position, a lock nut on said shoe, and a lock screw permanently supported on said heel engageable with said nut for locking said heel against displacement.
2. The combination with the foot portion of a shoe, of a detachable heel having a lip portion on its upper end, catch means engageable on sliding said heel longitudinally with said shoe for clamping said heel in position on said shoe, a lock screw extending through said lip portion, a lock nut in said shoe for receiving said lock screw when said heel is in position, and means for holding said lock screw permanently on said lip portion.
3. The combination with the foot portion of a shoe, of a detachable heel having a lip portion on its upper end, catch means engageable on sliding said heel longitudinally with said shoe for clamping said heel in position on said shoe, a sleeve extending through said lip portion, a lock screw revolvably held in said sleeve and extendable above the upper surface of said lip, and a lock nut in said shoe for receiving said screw and locking said heel against longitudinal movement.
4. The combination with the foot portion of a shoe, of a detachable heel having a lip portion on its upper end, catch means engageable on sliding said heel longitudinally with said shoe for clamping said heel in position on said shoe, a sleeve extending through said lip portion, a lock screw revolvably held in said sleeve and extendable above the upper surface of said lip, said screw having an enlarged head portion at its outer end and detents intermediate its ends for limiting the axial movement within said sleeve, and a lock nut in said shoe for receiving said lock screw.
5. The combination with the foot portion of a shoe, of a detachable heel having a lip

portion on its upper end, catch means engageable on sliding said heel longitudinally with said shoe for clamping said heel in position on said shoe, a sleeve extending through said lip portion, a lock screw revolvably held in said sleeve and extendable above the upper surface of said lip, said screw having an enlarged head portion at its outer end and detents intermediate its ends for limiting the axial movement within said sleeve, said sleeve having internal grooves extending axially over a portion of its length for receiving said detents and permitting said screw to be withdrawn flush with the upper surface of said lip portion, and a lock nut in said shoe for receiving said lock screw.

In testimony whereof, we have hereunto set our hands at San Diego, California, this 21st day of December, 1928.

IRA C. COLLIER.
